UNITED STATES PATENT OFFICE.

WILLIAM D. M. SIMMONS, OF BROOKLYN, NEW YORK, ASSIGNOR TO UNDERWOOD TYPEWRITER COMPANY, OF NEW YORK, N. Y., A CORPORATION OF DELAWARE.

DESIGN FOR A PIN.

Application filed February 19, 1925. Serial No. 12,428. Term of patent 14 years.

To all whom it may concern:

Be it known that I, WILLIAM D. M. SIMMONS, a citizen of the United States, residing in Brooklyn Borough, in the county of Kings, city and State of New York, have invented a new, original, and ornamental Design for Pins, of which the following is a specification, reference being had to the accompanying drawing, forming part thereof.

I claim:

The ornamental design for a pin, as shown.

WILLIAM D. M. SIMMONS.
